(57) **CLAIM**

The ornamental design for skateboard tool, as shown and described.

DESCRIPTION

FIG. 1 is a perspective view of the skateboard tool.

FIG. 2 is a rear elevation view of the skateboard tool.

FIG. 3 is a front elevation view of the skateboard tool.

FIG. 4 is a left side elevation view of the skateboard tool.

FIG. 5 is a right elevation view of the skateboard tool.

FIG. 6 is a top plan view of the skateboard tool.

FIG. 7 is a bottom plan view of the skateboard tool; and,

FIG. 8 is an exploded rear elevation view of the skateboard tool wherein the key is taken out from the handle.

The broken line showing is for illustrative purposes and forms no part of the claimed design.
